MATTHEW VIERENGEL, OF BROOKLYN, NEW YORK.

METHOD OF MANUFACTURING ENVELOPS.

1,208,413.

Specification of Letters Patent. Patented Dec. 12, 1916.

Application filed December 9, 1915. Serial No. 65,895.

To all whom it may concern:

Be it known that I, MATTHEW VIERENGEL, a citizen of the United States, and a resident of the city of New York, borough of Brooklyn, in the county of Kings and State of New York, have invented a new and Improved Method of Manufacturing Envelops, of which the following is a full, clear, and exact description.

10 The invention relates more specifically to the manufacture of what is known as clasp-fastening envelops.

The invention consists in cutting a continuous paper blank in a manner to provide 15 in the final product, gummed seams at the edges thereof; in moving the continuous blank past an operating station where a reinforcing member is added thereto prior to severing the sections of the blank which 20 form the ultimate product; in delivering metal clasping members to the blank prior to the severance of the sections thereof for attachment thereto and to the reinforcing member thereof; in punching an orifice in 25 the blank and in the reinforcing section thereof for registry with a clasp previously mounted in the blank; and in gumming, severing, and folding each section to form a completed envelop, the flap whereof is 30 shaped to register the orifice therein with the clasp in the body of the envelop.

Drawings.—Figure 1 is a view showing in perspective the blank from which the envelop is constructed in accordance with the 35 herein described method, and the completed article or envelop resulting from the performance of the said method; Fig. 2 is a similar view showing a modified form of blank and product resulting therefrom; Fig. 40 3 is a similar view showing a further modification of the form of the blank and the product resulting therefrom; Fig. 4 is a longitudinal section of an envelop constructed and arranged in accordance with 45 the present invention, the section being taken as on the median line of the envelop and through the clasp and the reinforcing member thereof, the section being taken as on the line 4—4 in Fig. 1; Fig. 5 is a transverse section of the same, the section being taken as on the line 5—5 in Fig. 1; Fig. 6 is a longitudinal section, on an enlarged scale, 50 of a modified form of the invention as shown in Fig. 2 of the drawings, the section being taken as on the line 6—6 in Fig. 2; Fig. 7 is a transverse section, on an enlarged scale,

of the form shown in Fig. 3, the section being taken as on the line 7—7 in Fig. 3; Fig. 8 is a longitudinal section of the same, the section being taken as on the line 8—8 in Fig. 3.

Description.—Heretofore envelops having metal clasps for fastening the same have been provided with large extensions overlapping at the center to form a double thickness for supporting said clasps in the service location thereof. The double seam thus formed at the center of the envelop has proved objectionable as it has necessitated the insertion of a tip within the envelop for 65 mounting or securing the metal clasp, an operation necessarily performed after the gumming of the lapped extensions referred to. A further objection incident to the former envelops has been that it necessitated 70 the double handling of the envelop in manufacture, first, constructing the same, and, second, applying the metal clasp thereto. These objections have been overcome by the 75 method set forth herein.

The preferred form of envelop is that shown in Fig. 1 of the drawings, wherein a full-sided face 12 is ultimately attached to narrow side seaming edges 13, to which it is secured by gummed edges 14 with which said face is provided, while the envelop is in the form of a blank 15. The blank 15 is cut from a continuous sheet to form a series of envelops, each having a back member 16, having seaming edges 13, a face member 12, and a flap member 17. The flap members 17 are, in the blank, partially severed from the face member 12 of the adjacent envelop, by cuts 18. When the blanks have been cut, the gum is applied to the edges 14 and to an area 19 extending over the flap members 17 and the face member 12 of the envelop blank adjoining. The gum may be applied to the area 19 in advance of the application to the edges 14. It is preferred, however, to apply the gum to both simultaneously. The gum having been applied, the next step in the operation is to overlay the gummed area 19 with a superimposed reinforcing strip 20. The strip 20 may be constructed from any suitable material, a good quality of tagboard being preferred by me. Simultaneous with the application of the strip 20, the edges 13 are overturned upon the back member 16 and in position to receive the gummed edges 14 of the envelop when overlaid upon the said edges 13. The next operation con-

sists in punching an orifice 21 in the reinforcing strip 20 and flap member 17, simultaneously therewith overturning the clip ends 22 of one of the clips 23 on the adjoining blank. At the moment of punching the strips 20 and the flap member 17, and overturning the ends 22, the blank is disposed so that the portion of the reinforcing strip 20 extends at both sides of the line of severance for the blank, which parts the successive envelopes from the blank. When, as shown best in Figs. 1 and 2 of the drawings, the face 12 is overturned on the edges 13, the clip 23 carried by the face 12, is laid over the back member 16 in position to register with the orifice 21 in the strip 20 when the blank 17 is overturned thereon.

It will be observed that when envelopes are constructed and arranged in accordance with the above described method, the portion of the envelop permanently holding the clip 23, is reinforced by a portion of the strip 20. It will also be observed that a portion of the said strip reinforces the material of the flap member 17 wherein is formed the orifice 21. Thus the two restraining members for holding the envelop closed, are both reinforced, while the appearance of the envelop is preserved as a full-faced article, no unsightly seam appearing in the face of said envelop.

As shown best in Figs. 5 and 7, the prongs 24 of the clips 23 extend upward through the orifice 21 when the flap member 17 is closed on the face 12 and overturned to prevent the separation of said flap and face. As shown best in Fig. 1 of the drawings, the clips 23 are delivered in position for attachment to the envelop blank as a continuous strip, the prongs 24 of the blank 40 being mutually connected, while the ends 22 are extended laterally in the same plane with the said prongs until just prior to arriving at position to be driven upward through the face 12 and strip 20, when the 45 said ends are upset as shown in the drawings.

Modification.—In Fig. 3 of the drawings, a modified form of blank is shown, wherein each back member 16 has at one side one of the seaming edges 13, while at the opposite side a longer extension forms an envelop face 25, the edge of which overlies the edge 13 to which it is secured by a gummed strip 26. Also the blank is modified by providing the back member 16 with a connecting extension 27, to which the flap 17 is directly attached. The extension 27 is overturned to form the bottom edge of the envelop when the envelop face 25 is turned thereover. A further modification in this form of envelop 60 consists in providing the smaller reinforcing sections 28 in the face 25, adjacent the edge thereof, and in providing the reinforcing rings 29 disposed on the flap members 17 in position to register with the clips 65 held by the sections 28, through which the

ends 22 are forced and upon which they are overturned.

In all forms of the invention, the portions of the blank from which the envelopes are formed, are severed after the reinforcing strip 20 and the clips 23 have been secured to the portions of the blank to which they pertain.

Claims:

1. The method of manufacturing envelopes 75 consisting in cutting a continuous blank having full-width face portions and full-width back portions, and lateral extensions to be united with said face portions; then applying gum to said blank as desired for uniting the portions thereof; then securing on said blank a reinforcing strip, portions of said strip being disposed adjacent the edge of the face and flap of the completed envelop; then mounting on said face and on the 80 reinforcement thereof, a closure clasp; and then severing the sections of said blank for folding the portions thereof to form completed envelopes.

2. The method of manufacturing envelopes 90 consisting in forming a continuous blank, the edges whereof are shaped to form a series of envelop-forming sections, each section providing a face portion, a back portion, a flap portion, and marginal extensions for holding said back and face portions in folded relation; then applying adhesive as desired; then placing a reinforcing strip upon said blank adjacent the edges 95 of the flap portion and adjoining face portion before said sections are severed from the continuous blank; then adding to said blank and to the reinforced portions thereof, a metal clasp member; then punching an orifice in said reinforcing strip adjacent the 100 edge of the flap portion; then severing the sections, the line of severance extending between each flap portion and the adjacent face portion, and through the reinforcing strip thereon placed; and then folding and 105 attaching the portions of the envelop by said adhesive.

3. The method of manufacturing envelopes consisting in forming a continuous strip blank having edges shaped to partially sever the same, said blank providing envelop-forming sections, each having a back portion, a face portion, and a flap portion, said portions being full width; then securing 115 near the edge of each of said face portions, a metal clasp, and forming in the flap portion adjacent thereto an orifice for receiving a similar clasp; then successively folding said sections to form the bodies of envelopes, and then severing the bodies so formed from 120 the strip blank, the line of severance passing between the flap portion of the envelop being removed and the face portion of the next succeeding section.

4. The method of manufacturing envelopes 130

consisting in forming a continuous blank of envelop-forming sections, each of said sections having a face portion, a back portion, and a flap portion of full width for forming a seamless body portion for each envelop; then moving said strip past a plurality of receiving stations; then successively applying to said blank portions, reinforcing strips, said strips overlying and connecting the portions of said blank forming the face and flap portions of separate envelopes when formed; then delivering a continuous strip of metal clasps for successively uniting the clasps to said blank strip and to the reinforced portions thereof adjacent the edges of said face portions; then folding the body portions of said blank to form envelopes; and then severing the formed portions from said blank. 15
